UNITED STATES PATENT OFFICE.

LOUIS W. WRIGHT, OF NEW HAVEN, CONNECTICUT, ASSIGNOR TO THE H. B. IVES COMPANY, OF NEW HAVEN, CONNECTICUT, A CORPORATION OF CONNECTICUT.

CASEMENT-ADJUSTER.

1,118,995.

Specification of Letters Patent.

Patented Dec. 1, 1914.

Application filed February 18, 1913. Serial No. 749,261.

To all whom it may concern:

Be it known that I, Louis W. Wright, a citizen of the United States, residing at New Haven, in the county of New Haven and State of Connecticut, have invented certain new and useful Improvements in Casement-Adjusters, of which the following is a specification, reference being had therein to the accompanying drawings.

My invention relates to a new and improved casement adjuster, having for its object, among other things, to provide means in a device of this character to prevent rotation of the post and that will also be available to increase the bearing surface upon the sill plate.

To these, and other ends, my invention consists in the casement adjuster, having certain details of construction and combinations of parts, as will be hereinafter described and more particularly pointed out in the claims.

Referring to the drawings, in which like numerals of reference designate like parts in the several figures; Figure 1 is a plan view of a casement adjuster having my improvements thereon; Fig. 2 is an enlarged sectional view thereof upon line A—B of Fig. 1; Fig. 3 is a similar view upon line C—D of Fig. 1; Fig. 4 is a perspective view of the post; and Fig. 5 is a perspective view of the lock plate.

The general design and structure of the casement adjuster as shown and described herein, except as modified by my invention, is the same as those now common in the art, there being a sill plate 1 that is secured to a window sill, having a slot 2 therein; a rod 3 pivotally and adjustably secured at one end to the sill plate, and at the other end pivotally secured to the sash plate 4, that is attached to the casement window. Heretofore there has been difficulty in holding the post, to which the rod is connected with the base member, against rotation within the sill plate, which very materially increases the longer the device is used, the parts being then more or less worn and the sill plate, in many cases, loosened upon the sill to which it is attached. When the post rotates, the sill plate end of the rod 3 cannot be securely held, and hence the casement window is not locked against movement.

In my invention I have provided a locking member that engages the post and sill plate

and holds the post against rotation irrespective of the measure of wear upon the parts, or the tightness of the sill plate upon the window sill, which locking member is designed to present the maximum friction surface upon the sill plate.

Referring now more particularly to my improvements, the numeral 5 designates the post, having an elongated head 6 thereon, with the slots 8 in the opposite ends thereof, and an intermediate head 7 of substantially the same width as the slot 2. The lock plate 9 has a circular portion 10 with an opening 11 therethrough, of substantially the same diameter as the post 5, and lips 12 at each end, of substantially the same width as the slot 2, that terminate at their lower ends in the fingers 13—13, of substantially the same width as the slots 8. When assembled, the intermediate head 7 is within the slot 2, the lock plate 9 upon the post 5, with the portion 10 resting upon the top of the sill plate, the lips 12 within the slot 2, and the fingers 13 thereon projecting down through the slots 8, and the rod 3 upon the post 5 between the lock plate 9 and thumb nut 14. Heretofore it has been the practice to have the head of the rod 3 in contact with the sill plate, but this is objectionable, as the leverage upon the rod causes it to work loose, and to remedy this difficulty by making the head larger is not desirable, because its size is then out of proportion to that of the adjacent parts and it thereby becomes unsightly in appearance.

With my device no rotating part is in contact with the sill plate, thereby minimizing the possibility of the parts being loosened, and I am enabled to obtain an enlarged frictional contact surface through the locking plate 9, without making the device appear either unsightly or cumbersome. With my lock plate cooperating with the head of the post, it is immaterial whether the intermediate head 7 is fitted nicely into the slot 2, or how much the same may become worn by use, as it is impossible for the post to turn, the lips 12 passing entirely through the slot 2 and the fingers thereon entering the slots 8.

In various ways my invention may be modified, and I therefore do not limit myself to the exact construction herein shown and described, but claim all that falls fairly within the spirit and scope of the appended claims.

Having described my invention, what I claim as new, and desire to secure by Letters Patent, is:—

1. In a device of the character described, 5 the combination with the sill plate, having a slot therein; of a post within said slot; and a lock plate contacting with the top surface of said sill plate and having members thereon that pass through said slot and engage the head of said post to prevent the rotation thereof whereby both said post and lock plate are held against relative rotation in said sill plate.
2. In a device of the character described, 15 the combination with the sill plate, having a slot therein; of a post within said slot; and a lock plate upon said post contacting with the top surface of said sill plate and having a part thereon that passes through said slot 20 and engages the head of said post to prevent the rotation thereof as well as said lock plate.
3. In a device of the character described, 25 the combination with the sill plate, having a slot therein; of a post within said slot, having a head with a slot therein; and a lock plate contacting with the top surface of said sill plate and having a part thereon that passes through the slot in said sill plate 30 and enters the slot in the said head to prevent rotation of said post and said lock plate.
4. In a device of the character described, the combination with the sill plate, having a

slot therein; of a post within said slot, having a slotted head thereon; and a lock plate upon the opposite side of said sill plate from said head, having parts thereon that pass through the slot in said sill plate and enter the slots in said head to prevent rotation of said post and lock plate. 35 40

5. In a device of the character described, the combination with the sill plate, having a slot therein; of a post within said slot; and a lock plate upon said post, a portion 45 of which is wider than said slot and contacts with the upper surface of said sill plate, and having a lip thereon that projects through said slot and engages the head of said post to prevent the rotation thereof and 50 said lock plate.

6. In a device of the character described, the combination with the sill plate, having a slot therein; of a post within said slot; and a lock plate contacting with the upper surface of said sill plate and terminating at each end in a lip that passes through said slot to prevent the rotation of the lock plate, and said lips having a finger thereon 55 that engages the head of said post to prevent the rotation thereof of said post. 60

In testimony whereof I affix my signature in presence of two witnesses.

LOUIS W. WRIGHT.
